UNITED STATES PATENT OFFICE

JOHN R. ROGERS, OF BROOKLYN, NEW YORK, ASSIGNOR TO MERGENTHALER LINOTYPE COMPANY, A CORPORATION OF NEW YORK

TYPOGRAPHICAL DISTRIBUTING MACHINE

Application filed November 27, 1928. Serial No. 322,115.

This invention relates to typographical distributing machines, such as linotype machines of the general organization represented in U. S. Letters Patent to O. Mergenthaler, No. 436,532, wherein circulating matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter returned through a distributing mechanism to the magazine from which they started. In some machines, such as the commercial model 9, where matrices may be drawn from several magazines and mixed together in the same line, the distributing mechanism includes a primary distributor which first sorts the matrices according to font, and a plurality of main distributors which thereafter sort the matrices of the individual fonts according to character and restore them to their proper channels in the magazines. With this type of distributing mechanism, the matrices, after font separation, pass down chutes or tubes and enter so-called lower distributor boxes wherein they are guided upon inclined rails into engagement with reciprocating pawls or escapements, which feed them one at a time to the main distributors. In order that these pawls or escapements may cooperate properly with the matrices, the latter are usually provided in their bottom edges with central notches which necessarily vary in shape and depth according to the thickness of the individual matrices. Besides adding to the cost of production, such notches in the matrices materially limit the space ordinarily required for the regular font notches and, moreover, seriously weaken the matrices, especially when the latter are formed with other necessary cuts or notches. Furthermore, matrices comprising fonts used on other machines, such as those of the single distributor class, are excluded from use on machines of the multiple distributor class described, since they do not have the required central notches.

The present invention is intended to obvi-

ate the foregoing difficulties and contemplates certain improvements whereby the distributing mechanism may receive and handle matrices of all fonts whether they have or have not the objectionable central notches referred to. To this end, each of the lower distributor boxes is provided with an escape-
55 ment device arranged preferably to cooperate with the upper ends of the matrices, and which device not only serves its primary purpose of feeding the matrices one by one to the distributor screws, but also acts to accelerate the delivery of the individual matrices to the screws. In the preferred embodiment illus-
60 trated, there is employed a single vertically reciprocating member presenting matrix ar-
65 resting and releasing dogs arranged to operate in offset parallel planes and adapted by the reciprocation of said member to effect the separation and escape of the gravitating 70 matrices in the manner required.

In the accompanying drawings, the invention has been shown merely in preferred form and by way of example, and as applied to the specific type of distributing mechanism indicated. However, many changes and variations may be made therein and in its mode of application, which will still be comprised within its spirit. It is to be understood, therefore, that the invention is not limited 80 to any specific form or embodiment, except insofar as such limitations are specified in the claims.

Referring to the drawings

Fig. 1 is a rear elevation of the receiving end of a multiple distributor showing the lower distributor box broken away and equipped with the present improvements;

Fig. 2 is a face view of an ordinary matrix.

Figs. 3 and 4 are fragmentary sections through the lower box showing the escape-
85 ment device in different positions during its operation, Fig. 3 being a section taken on the line 3-3 of Fig. 6;

Fig. 5 is a front elevation of the lower box detached;

Fig. 6 is a horizontal section taken on line 6-6 of Fig. 3; and

Figs. 7 and 8 are face and edge views, re- 100

spectively, of the improved escapement device detached.

After casting, the matrix line is transported to the upper distributor box A where the individual matrices are successively detached from the line by the lifting finger A¹ for delivery to the upper or lower distributor, according to the font to which they belong. The two distributors are identical in construction, each comprising a longitudinally ribbed bar B and a set of conveying screws B¹ which carry the matrices therealong. After the matrices are detached from the line, they are presented to the conveying screws B¹ of the upper distributor but, before they reach the corresponding distributor bar B, they are subjected to the action of the font selecting bridge C, which is adapted to cooperate with the lower ends of the matrices and control their delivery according to font to the upper or lower distributor. The matrices X are of the usual construction, each being formed at its four corners with the projecting ears x and at its upper end with the V-shaped notch x¹ having the distributing teeth x². The matrices of one font (those delivered to the lower distributor) are formed at their lower ends with the ordinary front notches x³, while the matrices of the other font (those delivered to the upper distributor) are without the notches x³ or have them located in a different position along their bottom edges. Consequently, when the matrices are presented to the selecting bridge C, those without the font notches are supported by said bridge at such level that their distributing teeth x² are caused to engage the upper distributor bar B while those of the other font, due to the presence of the notches x³, straddle the bridge C and drop to a lower level so that their distributing teeth will avoid engagement with the upper distributor bar. These latter matrices, when straddling the selecting bridge, are supported by their upper projecting ears upon the guide rails A² and are carried along these rails and dropped into the chute C¹ leading downwardly to the lower distributor box D. The matrices pass by gravity through the box D, wherein they are supported by the inclined rails D¹, and are fed one by one under the control of an escapement into the threads of the conveying screws B¹ of the lower distributor, whence they are carried along the associated bar B for final distribution.

So far as described, except as hereinafter pointed out, the parts are or may be of any well-known or approved construction and in themselves constitute no part of the present invention, which is directed primarily to an improved escapement device for the lower distributor box D intended to control the passage of the gravitating matrices one at a time into position to be picked up by the screws irrespective of the presence or absence

of the objectionable central notches hereinbefore mentioned.

As shown in Figs. 3 to 8 inclusive, the improved escapement device comprises a vertically reciprocating slide E mounted in guideways D³ of a supporting block D² which constitutes a fixed part of the lower distributor box D. The slide E is formed on its rear face with a lug or ear E¹ and has a pair of depending side arms E² and an intermediate depending finger E³. The arms E² are arranged alongside the outer side faces of the respective guide rails D¹ and are formed at their lower ends of a pair of integral lugs E⁴, (Fig. 3), which project inwardly from said arms so as, in one position of the slide E, to be disposed above the upper edges of the guide rails in the path of the upper ears of the descending matrices, and so as, in another position of the slide, to be disposed below the rail edges out of the path of the matrices. In order to provide room for the lugs E⁴, the outer side faces of the guide rails D¹ are recessed or cut away at d', see Fig. 5. The finger E³ is offset in relation to the lugs E⁴ and is adapted, as the slide E reciprocates, to accelerate the escape of the leading matrix and hold back the following matrices. However, instead of cooperating with the ears of the matrices, the finger E³ is arranged to engage the matrices at the bottom of the V-shaped distributing notch x¹, but its relation to the lugs E⁴ is such that, when the slide E is moved downwardly from its upper position (shown in Fig. 3), the rear face of the finger will pass in front of a succeeding matrix, and as the top edges of the lugs E⁴ become flush with the guide rails D¹, the lower edge of the finger is caused to engage the leading matrix at the point stated and thus to hasten its escape to the screws. When the slide is moved upwardly, the finger E³ is carried above the bottom of the notch x¹ of what was the succeeding matrix and allows it to slip forwardly against the lugs E⁴, the latter in the meantime having moved above the guide rails D¹. The cooperation of the finger E³ with the matrices is facilitated by the presence of the customary central slot x⁴ cut in the rear face of each matrix, as shown in Figs. 3 and 4, and which is adapted to receive the finger E³ as the slide E is depressed. As is well understood in the art, these centrally located slots are intended to provide at the upper ends of the matrices at the bottom of the distributing notches x¹ portions of uniform thickness which, in cooperation with the usual separator bar or blade located at the exit end of the upper distributor box, prevent more than one matrix at a time from being elevated from the composed line by the lifting finger A¹. It is with these uniform portions that the finger E³ is adapted to engage.

The finger E³ and lugs E⁴ thus constitute upper and lower matrix arresting and releas-

ing dogs operating in adjacent parallel planes, the lower dogs E^4 having their rear or matrix contacting faces disposed in a vertical plane which is slightly in advance of the corresponding face of the upper dog E^3 .

5 When the reciprocating slide E occupies its upper position (as shown in Fig. 3), the lower dogs E^4 stand partially above the upper edges of the guide rails D^1 to engage the lower ends of the upper ears of the matrices; whereas, when the slide is in its lower position (Fig. 4), said dogs stand below the rail edges to allow the matrices to pass over the same on their way to the screws. In this 10 connection, it may be observed that the top faces of the lugs E^4 are beveled or inclined to correspond with the inclination of the upper edges of the guide rails D^1 . The upper dog or finger E^3 , on the other hand, stands clear 15 of the descending matrices in the upper position of the slide E , but moves downwardly with the slide into the path of a matrix as the lugs E^4 pass below the upper edges of the guide rails. With this arrangement, as the 20 slide E is raised a matrix will be released by the upper dog E^3 and allowed to slip forwardly against the lower dogs E^4 , which at such time are above the rails in position to engage the lower ends of its upper projecting ears; but on the return movement of the 25 slide, said matrix will be free to pass over the dogs E^4 while the upper dog E^3 holds back the next succeeding matrix.

In order to compensate for slight differences in the depth of the distributing notches x^1 in various matrices, which is due to carelessness in cutting the transverse clearance notch x^5 (Fig. 2) located at the bottom of the combination web, the finger E^3 is mounted in the slide E so as to be capable of yielding vertically when it engages the leading matrix. In the present instance, the finger is provided with an offset cylindrical portion G^1 which is mounted for vertical movement 40 in a recess E^7 formed in the bottom of the slide E and which is sustained therein by means of a pin and slot connection G^2 , the finger being held resiliently downward in a normal position by a light compression spring G^3 arranged in the recess E^7 above the cylindrical portion G^1 .

The means employed for operating the slide E (see Figs. 1, 3 and 6) include a rock shaft F journaled transversely in the block D^2 adjacent the ear E^1 before mentioned. At one end, the shaft F projects through the rear side wall of the block D^2 where it is provided with a crank arm F^1 , and between the two side walls of said block, the shaft has 55 fast thereto a fixed sleeve F^2 formed with a pair of short horizontally disposed lever arms F^3 . These arms F^3 embrace the ear E^1 and are loosely connected thereto by a cross pin e which extends through the ear and 60 engages in open slots f formed in the ends of

the arms F^3 . Hence, by operating the crank arm F^1 upwardly and downwardly, the shaft F is turned in opposite directions and, through the lever arms F^3 , causes reciprocation of the slide E . In the present instance, 70 the crank arm F^1 is actuated by the rocker arm A^3 of the lifting finger A^1 for the upper distributor box A through suitable link connections carried by the block D^2 , the arm A^3 being in turn operated in the customary way 75 by the rotary cam B^2 and the pull spring A^5 . The said connections, see Figs. 1 and 5, comprise a vertically disposed link member F^4 pivotally fastened at its lower end to the crank arm F^1 and abutting at the top against a depending finger piece A^4 secured to the rocker arm A^3 . This particular form of broken joint permits the lower distributor box D and its escapement to be readily and 80 instantly removed from and replaced in the machine, as is desirable. Since the rocker arm A^3 is capable of actuating the shaft F in one direction only, namely, to depress the slide E , the rotation of the shaft in the opposite direction is effected by a pull spring 85 F^5 anchored to the box D and connected to the longer arm F^7 of a lever F^6 which is pivoted directly above the shaft F to the block D^2 . The other arm F^8 of this lever, which is 90 pivotally connected to the link member F^4 , 95 is arranged parallel to the crank arms F^1 , so that said link member will be sustained in a vertical position at all times without other means of support. Through these connections the reciprocation of the slide E is effected and controlled by the operation of the rocker arm A^3 and will therefore take place 100 at the required speed and in synchronism with the lifting finger A^1 .

According to the foregoing arrangement and assuming the parts to be in the position shown in Figs. 1 and 3 with the lower dogs or lugs E^4 in their arresting position above the guide rails D^1 , it will now be seen that, as the link member F^4 is depressed by the arm A^3 , 105 the shaft F will be rotated and cause the lever arms F^3 to move the slide E downwardly against the tension of the spring F^5 . When the lugs E^4 become flush with the upper edges of the guide rails D^1 , the leading matrix will 110 be free to escape and the upper dog or finger E^3 will have been moved in front of the next succeeding matrix (see Fig. 4). However, due to the offset relation of the two sets of dogs, the leading matrix in escaping will be 115 engaged and depressed by the upper dog E^3 as the downward movement of the slide E is completed, the dog E^3 thus serving the double function of accelerating the escape of the leading matrix and holding back the following matrices. Since the matrices vary widely 120 in thickness according to character and font, the horizontal distance between the rear faces of the respective sets of dogs E^3 , E^4 , is made 125 equal to or slightly less than the thickness of 130

the thinnest matrix, so that only one matrix at a time is allowed to escape to the screws. On the return or upward stroke of the slide E, which is effected by action of the spring F⁵, under control of the rocker arm A³, the lugs E⁴ are moved upwardly into their arresting position above the guide rails D¹ and the finger E³ out of engagement with what is now the leading matrix, which, being thus released, is allowed to slide forwardly by gravity against the lugs E⁴. The spring F⁵ not only provides the required element of safety in the upward movement of the slide E, but it also serves to maintain the escapement device yieldingly in a convenient position when the box D is removed from the machine, the slide E at such time banking at the top of the guideway D³ of the supporting block D². It may also be observed, by reference to Fig. 1, that the arm A³ in depressing the slide E is actuated by its control spring A⁵, so that any danger of damage to the parts that might be caused by a matrix becoming wedged between the escapement lugs and the guide rails is avoided.

The removal of the lower distributor box D may be effected in the usual manner, it being slidably mounted for endwise horizontal movement in a supporting bracket H detachably connected by screws H¹ to the lower distributor bar. Since a portion of the connections between the lifting finger A¹ and the escapement slide E are mounted upon and carried by the removable box as above described, while the remaining portion of the connections (being connected to the operating lever A³) are mounted independently of the box, the removal and replacement of the box automatically breaks and makes an operative connection between the lifting finger and escapement slide.

As previously stated the invention has been shown herein only by way of example, and obviously it is susceptible of many modifications and variations without departing from its scope.

Having thus described my invention, its construction and mode of operation, what I claim and desire to secure by Letters Patent of the United States is as follows:

1. In a typographical distributing mechanism comprising a distributor bar and a set of matrix conveying screws, the combination of inclined guide rails along which the matrices gravitate toward the screws, and an escapement device presenting upper and lower matrix arresting and releasing dogs movable rectilinearly and arranged to operate in offset vertical parallel planes in controlling the passage of the gravitating matrices one at a time into position to be picked up by the screws.

2. In a typographical distributing mechanism for handling matrices formed on their opposite edges with upper and lower project-

ing ears, and comprising a distributor bar and a set of matrix conveying screws, the combination of inclined guide rails along which the matrices gravitate toward the screws, and an escapement device presenting a pair of vertically reciprocating dogs arranged to cooperate with the lower ends of the upper projecting ears of the matrices in controlling the passage of the matrices one at a time into position to be picked up by the screws.

3. In a typographical distributing mechanism for handling matrices formed on their opposite edges with upper and lower projecting ears, and comprising a distributor bar and a set of matrix conveying screws, the combination of inclined guide rails along which the matrices gravitate toward the screws, and an escapement device presenting upper and lower reciprocating dogs for controlling the passage of the gravitating matrices one at a time into position to be picked up by the screws, an upper dog being arranged to engage the upper ends of the matrices, and the lower dogs arranged to engage the lower ends of the upper projecting ears of said matrices.

4. In a typographical distributing mechanism for handling matrices formed on their opposite edges with upper and lower projecting ears and comprising a distributor bar and a set of matrix conveying screws, the combination of inclined guide rails along which the matrices gravitate toward the screws, and an escapement device presenting upper and lower matrix arresting and releasing dogs movable rectilinearly and arranged to operate in offset parallel planes in controlling the passage of the gravitating matrices one at a time into position to be picked up by the screws, an upper dog being arranged to engage the upper ends of the matrices and the lower dogs arranged to engage the lower ends of the upper projecting ears of the matrices.

5. In a typographical distributing mechanism comprising a distributor bar and a set of matrix conveying screws, the combination of inclined guide rails along which the matrices gravitate toward the screws, and an escapement device for controlling the passage of the matrices one at a time into position to be picked up by the screws, said device consisting of a vertically reciprocating member having upper and lower matrix arresting and releasing dogs arranged in relatively fixed offset parallel planes.

6. A combination as set forth in claim 5, characterized by the fact that the distance between the vertical planes of the upper and lower matrix arresting and releasing dogs therein referred to is equal to or slightly less than the thickness of the thinnest matrix, for the purpose described.

7. In a typographical distributing mechanism comprising a distributor bar and a set of matrix conveying screws, the combination

of inclined guide rails along which the matrices gravitate toward the screws, and an escapement device consisting of a vertically reciprocating member carrying two sets of 5 matrix arresting and releasing lugs arranged in relatively fixed offset parallel planes and adapted by the reciprocation of said member to alternately engage the matrices in controlling their passage one at a time into position to be picked up by the screws.

8. In a typographical distributing mechanism for handling matrices centrally notched at their upper end and formed on their opposite edges with upper and lower projecting ears, said mechanism comprising a distributor bar and a set of matrix conveying screws, the combination of inclined guide rails along which the matrices gravitate toward the screws, and an escapement device controlling the passage of the gravitating matrices one at a time into position to be picked up by the screws, said device consisting of a vertically reciprocating member provided at its opposite sides with a pair of integral lugs 25 or projections and with a central depending finger offset in relation thereto, the lugs in the upper position of said member acting to arrest the leading matrix by engaging the lower ends of the upper projecting ears thereof and in the lower position of the member standing clear of said matrix to permit its escape, and the depending finger when said member is in its upper position standing clear of the descending matrices to permit the leading matrix to be arrested by the lugs but acting, as the member is moved downwardly, to hold back the following matrices by engaging portions thereof at the bottom of their central notches.

40 9. A combination as specified in claim 8, characterized by the fact that the spacing of the lugs therein referred to is such that, as the reciprocating member completes its downward stroke, the depending finger acts also to depress the leading matrix and accelerate its escape.

50 10. In a typographical distributing mechanism comprising a distributor bar and a set of matrix conveying screws, the combination of inclined guide rails along which the matrices gravitate toward the screws, an escapement device presenting upper and lower matrix arresting and releasing dogs movable rectilinearly and arranged to operate in offset vertical parallel planes in controlling the passage of the gravitating matrices one at a time into position to be picked up by the screws, a block wherein the escapement device is mounted, and means carried 55 by the block for actuating said device.

60 11. In a typographical distributing mechanism comprising a distributor bar and a set of matrix conveying screws, the combination of inclined guide rails along which the matrices gravitate toward the screws, an escape-

ment device arranged to cooperate with the upper ends of the matrices for controlling their passage one at a time into position to be picked up by the screws, and means for operating said escapement device yieldingly 70 in both directions to avoid damage to the parts in the event of a jammed matrix.

12. In a typographical distributing mechanism, the combination of an upper distributor box having a lifting finger for feeding the 75 matrices one at a time therefrom, a lower distributor box having an escapement device for controlling the passage of the matrices one at a time therefrom, said lower distributor box and its escapement device being removable from the machine as a unit, and connections between the lifting finger and the escapement device, said connections being arranged to be automatically made and broken 80 as the lower distributor box is placed in and removed from the machine respectively.

13. In a typographical distributing mechanism, the combination of an upper distributor box having a lifting finger for feeding the 85 matrices one at a time therefrom, a lower distributor box having an escapement device for controlling the passage of the matrices one at a time therefrom, said lower distributor box and its escapement device being removable from the machine as a unit, and connections between the lifting finger and the escapement device, said connections being mounted in part upon the lower distributor box and mounted in part independently thereof and arranged to permit the free and 90 unimpeded removal and replacement of said matrices.

14. A combination as specified in claim 8, characterized by the fact that the central depending finger therein referred to is mounted to yield vertically in the reciprocating escapement member, for the purpose described.

15. An escapement slide for controlling the passage of matrices through the lower distributor box of a typographical distributing machine, said slide comprising a body portion, a pair of arms depending therefrom at its opposite edges and spaced apart sufficiently to allow a matrix to pass between them, said arms being formed at their lower ends with inwardly projecting lugs adapted to cooperate with the lower ends of the upper projecting ears of the matrices.

16. An escapement slide for controlling the 110 passage of matrices through the lower distributor box of a typographical distributing machine, said slide comprising a body portion, a pair of arms depending therefrom at its opposite edges and spaced apart sufficiently to allow a matrix to pass between them, said arms being formed at their lower ends with inwardly projecting lugs adapted to cooperate with the lower ends of the upper projecting ears of the matrices, and a member 115 also carried by the body portion in offset re- 120 125 130

lation to said lugs and adapted to cooperate with the upper ends of the matrices.

17. An escapement slide for controlling the passage of matrices through the lower distributor box of a typographical distributing machine, said slide comprising a body portion, a pair of arms depending therefrom at its opposite edges and spaced apart sufficiently to allow a matrix to pass between them, said arms being formed at their lower ends with inwardly projecting lugs adapted to cooperate with the lower ends of the upper projecting ears of the matrices, and a centrally located finger also depending from the body portion and arranged in offset relation to said lugs and adapted to cooperate with the upper ends of the matrices at the base of the distributing notch formed therein.

18. In testimony whereof, this specification has
20 been duly signed by

JOHN R. ROGERS.
